W. W. DEAN.

HARMONIC SIGNALING DEVICE FOR TELEPHONE SYSTEMS.
APPLICATION FILED SEPT. 9, 1905.

UNITED STATES PATENT OFFICE.

WILLIAM W. DEAN, OF ELYRIA, OHIO; CURTIS B. CAMP, TRUSTEE, APPOINTED BY COURT.

HARMONIC SIGNALING DEVICE FOR TELEPHONE SYSTEMS.

1,125,494.

Specification of Letters Patent. Patented Jan. 19, 1915.

Application filed September 9, 1905. Serial No. 277,687.

To all whom it may concern:

Be it known that I, WILLIAM W. DEAN, a citizen of the United States, residing at Elyria, in the county of Lorain and State 5 of Ohio, have invented certain new and useful Improvements in Harmonic Signaling Devices for Telephone Systems, of which the following is a specification, reference being had therein to the accompanying 10 drawing.

My invention relates to selective signaling systems, and particularly to receiving devices for use therein.

It has for its object the improvement and 15 simplification of such devices.

Specifically stated my invention comprises a polarized selective ringer for harmonic signaling. In such ringers as I have heretofore disclosed them the structure is 20 similar to that of an ordinary polarized bell except that the armature instead of being pivoted is mounted upon a stiff spring secured by its ends so that the resilience of the spring permits movement of the armature and re-acts in such fashion as to supplement the effects of the current. Each ringer made according to my present invention has a definite period, and will respond to current of a definite frequency only. I 25 attain this result by suitably proportioning the three constants of length, mass and tension, of the clapper-rod and connected parts. In the present case I provide the armature with a simple form of pivot support, and 30 connect a stiff spring therewith, providing adjustments for the latter such that the armature may be exactly placed and its motion accurately determined. The tension of my spring is also made adjustable, which 35 40 I consider an important feature.

My invention is illustrated in the accompanying drawings wherein:

Figure 1 is a top plan view as mounted 45 of a ringer with my improvements; Fig. 2 is a side view thereof; Fig. 3 is a rear end view thereof; and Figs. 4 and 5 are respectively top plan and rear end views of modified armature connections.

Referring to the drawings A indicates a 50 pair of spools mounted upon soft iron cores carried by the iron yoke B, which also carries the gongs G, mounted on posts g which may be adjusted to and from the center of the yoke by means of the worms b. The 55 yoke also carries the permanent magnet M

by which the armature and cores are normally polarized.

Carried upon the rear end of the cores of the magnets A is a brass yoke Y, secured by lock nuts y, which may be threaded either 60 directly on the pole piece or upon the sleeve carried upon the magnet head. The yoke has its ends provided with lateral tongues y', which are bent back and returned in a plane parallel to that of the main body of 65 the yoke. The armature A' is mounted directly opposite the pole pieces, and provided with a stiff spring a screwed or riveted to it, whose opposite ends extend past the bent tongues of the yoke, and rest upon the points 70 of set screws y² which are tapped therein. This arrangement is particularly shown in Figs. 1, 2 and 3. Since the spring is not rigidly fastened to the yoke spring it is 75 necessary to provide independent means for supporting the armature, so I produce a simple form of pivot support by dropping two studs y³ from the body of the yoke Y, each stud having a slight depression in its 80 end, and receiving the pointed tip of a screw y³⁰ tapped up through the armature and held by a suitable lock-nut. The downward pressure of the two ends of the spring a against the screws y² throws the armature 85 forward so as to hold the screws y³⁰ permanently in engagement with the studs y³, and as the armature is vibrated by the magnets it rocks upon the studs against the tension one way or the other of the spring a.

In Figs. 4 and 5 I have shown a modified 90 form of pivot support, with a corresponding modification in the spring a. Here the yoke Y has dropped ends y', carrying screws y² as before; but the screws point downward, and the spring a presses up- 95 ward, in a fashion the reverse of that shown in Figs. 1, 2 and 3. The consequent downward pull on the armature necessitates a pivot, hence in this case I employ a pair of drop ears y⁴, with pivot point and screw as 100 seen in ordinary ringers. The adjustment and operation of this device are the same as those of the other.

It is to be noted that the present improvements are of such a nature that they can 105 readily be applied to ordinary ringers of my standard type, having a yoke carried on the ends of the cores, all that is necessary being to substitute the new yokes, armatures and clapper-rods, for the old ones.

Having thus described my invention what I claim and desire to secure by Letters Patent is:

1. In a selective harmonic ringer, an electro-magnet, a pivoted armature, and a spring normally maintaining the armature in an intermediate position, said spring having its major axis lying parallel to that of the armature, and means to adjust the tension thereof, substantially as described.
2. In a selective harmonic ringer, an electro-magnet, a pivoted armature, and a spring normally maintaining the armature in an intermediate position, an intermediate point of said spring secured to the armature and the ends of said spring resting against supports, substantially as described.
3. In a selective harmonic ringer, an electro-magnet, a pivoted armature, and a spring normally maintaining the armature in an intermediate position, the middle of said spring secured to the armature and the

ends of said spring adjustably supported, whereby its tension may be changed and the armature adjusted at will, substantially as described.

4. A harmonic selective signal device comprising a double electro-magnet, a carrying yoke therefor, a pair of gongs adjustably mounted thereon, a polarizing magnet, an armature yoke carried upon the free ends of the magnet cores, a pivotal connection between the yoke and the armature, and a tension spring secured at an intermediate point to the armature, together with adjustable supports in the yoke for the ends of the tension spring, substantially as described.

In testimony whereof I affix my signature in presence of two witnesses.

WILLIAM W. DEAN.

Witnesses:

RAY H. MANSON,
S. A. BEYLAND.
